UNITED STATES PATENT OFFICE.

ROBERT GALBRAITH, OF LANSINGBURG, ASSIGNOR TO MERRITT PECKHAM,
OF UTICA, NEW YORK.

DESIGN FOR A HEATING-STOVE.

SPECIFICATION forming part of Design No. 17,909, dated November 29, 1887.

Application filed October 14, 1887. Serial No. 252,402. Term of patent 7 years.

To all whom it may concern:

Be it known that I, ROBERT GALBRAITH, a citizen of the United States, residing in the village of Lansingburg, in the county of Rensselaer and State of New York, have invented and produced a new and original Design for Heating-Stoves, of which the following is a specification, reference being had to the accompanying engraving, representing said de-

sign.

The primary distinctive feature of my design is the shape of the stove, consisting of the four-sided lower section, A, the upper four-sided section, B, and the intermediate columnar section embracing the outer columns, C, tapered at their upper portions, and the inner column, D, tapered at its lower part.

Another feature is the design for the lower section, consisting of the quadrilateral hearth-plate f, having rounded corners f', the four-sided overhanging upper plate, g, having rounded corners g', the upright quadrilateral side plate, h, having the rounded end parts, h', and the upright four-sided front plate, i, 25 curved outwardly and furnished with the upper panel, j, and lower ones, k.

Another feature is the design for the upper section, consisting of the lower quadrilateral plate, l, having rounded corners l', the quadrilateral top plate, m, having rounded corners, and the molded upwardly-inclined portion m', the oblong upright side plate, n, rounded at its ends n', and the oblong upright front plate, o, having the lateral raised panels p and the 35 intervening raised oblong panel, q.

Another feature is the design for the columnar section, consisting of the four outer columns, C, having their upper portions tapered and their lower parts furnished with the panels r, and the inner column, D, having its lower 40 portion tapered and its upper part cylindrical and furnished with the panel s.

The top crest, x, foot-rest y, and feet z are not of this design.

I claim—

1. The design for a heating-stove, consisting of the lower section, A, upper section, B, and the intermediate columnar section, shaped and ornamented substantially as described and shown.

2. In a design for a heating-stove, the lower section, consisting of the hearth-plate f, upper plate, g, side plate, h, and front plate, i, with panels j, k, shaped and ornamented substantially as described and shown.

3. In a design for a heating-stove, the upper section, consisting of the lower plate, l, top plate, m, side plate, n, and front plate, o, with panels p, q, shaped and ornamented substantially as described and shown.

In testimony whereof I hereunto set my hand, in the presence of two subscribing witnesses, this 23d day of September, 1887.

ROBT. GALBRAITH.
